CYCLE SADDLE

Robert H. Mesinger, Lakecrest Drive, Aunt Hack Ridge,
Danbury, Conn. 06810

Filed June 7, 1968, Ser. No. 12,249

Term of patent 14 years

Int. Cl. D12—11, 14

U.S. Cl. D90—16

Fig. 2

Fig. 3

Fig. 1

FIG. 1 is a side elevational view of a cycle saddle embodying my new design;

FIG. 2 is a plan view thereof; and

FIG. 3 is front elevational view thereof.

The saddle support, shown fragmentarily and in broken lines, is included for illustrative purposes only.

I claim:

The ornamental design for a cycle saddle, substantially as shown and described.
